STEPHEN HAMMER, OF PORTLAND, OREGON, ASSIGNOR OF ONE-HALF TO THOMAS A. CLARKE, OF PORTLAND, OREGON.

MITER-TOOL.

1,095,149.

Specification of Letters Patent. Patented Apr. 28, 1914.

Application filed January 9, 1913. Serial No. 740,966.

To all whom it may concern:

Be it known that I, STEPHEN HAMMER, a subject of Finland, Russia, residing in the city of Portland, county of Multnomah, and 5 State of Oregon, have invented certain new and useful Improvements in Miter-Tools, of which the following is a specification.

My invention relates to miter tools, and more particularly to a tool adapted to be 10 placed either in an angle, or around an angle formed by two meeting lines or surfaces, and which can be easily adjusted for the purpose of accurately dividing or bisecting the angle and indicating the cut in 15 forming a mitered joint.

Among the salient objects of the invention are,—to provide a tool of the character referred to which is equally adapted for use in, or around, an angle; to provide a tool 20 of the character referred to which requires no calculation, but needs simply to be closed half way in order to determine the angle of the miter, and to this end the members which are pivoted together to constitute this tool are provided longitudinally 25 thereof with marks or indications for use in adjusting the parts or members and for indicating when they have been closed half way from any opening to which they have 30 been adjusted; and, in general, to provide a greatly simplified and a much less expensive tool of the character referred to which is extremely simple in its operation and accurate in its indications.

35 The invention will be readily understood from the following description of one practical embodiment thereof, fully illustrated on the accompanying sheet of drawings, forming a part hereof, and in which—

40 Figure 1 is a side elevation of the invention, showing different positions of adjustment in dotted lines; and Fig. 2 is an edge view thereof.

In the drawings, a very simple form or 45 embodiment of the invention is shown, comprising two members 1 and 2 pivotally connected at or near their ends by means of a pivot 3, placed at points coincident with their middles, measured crosswise. I prefer to form the member 1 of two flat pieces of 50 metal, spaced apart, as indicated, with the member 2 pivoted therebetween, and adapted to be closed knife fashion, thereby folding into a very compact form. The ends 55 which are pivotally connected are rounded

to a form concentric with the pivotal axis, so that when the parts are opened to any angle relative to each other, there are no corners or projections which would prevent the tool from being placed in any angle, 60 with the straight outside edges resting flat against the surfaces forming the angle. The member 1 is provided along its inner straight edge with a series of close, equally spaced graduation marks, as at 4. It will 65 be noted that the members 1 and 2 are of the same width, in the form here shown, thereby adapting it for use in or around an angle, said members each having straight edges at both sides. The member 2 is pro- 70 vided longitudinally thereof and along its middle with a center or half way line, as 5, which, if extended, would intersect the pivotal axis of the members 1 and 2. The edges of the member 2 are straight and parallel 75 with each other, and with the line 5, and are equidistant therefrom at all points. The point on the inner or graduated edge of the member 1, at which the inner edge of the member 2 intersects it when the tool has 80 been adjusted in or around an angle, is the point to which line 5 of the member 2 should be moved to ascertain the miter angle, or the cut for a mitered joint be- 85 tween two bodies or surfaces to be thus joined. It is necessary, therefore, to pro- vide a series of close, equally spaced graduation marks along the inner edge of the member 1. For example, the members 1 and 90 2 are shown in full lines to be standing at right angles to each other. The inner edge of the member 2 intersects or crosses the edge of the member 1 at a point on the graduation marked "10," as indicated by the numeral 6. To ascertain the angle for a 95 proper cut to make a mitered joint between two members or objects to be joined at right angles, it is only necessary to close the member 2 until the middle line 5 thereof inter- 100 sects or crosses the edge of the member 1 at said point "10," indicated by 6, as shown by the dotted line position A. Inasmuch as the edges of the member 1 are both straight and parallel with each other and with the middle line 5, either edge thereof can be 105 used to mark or indicate the angle on which the cut is to be made for the mitered joint. If the angle of the two meeting bodies is greater than a right-angle, as for example, requiring that the member 2 should be 110

opened out to the position *c*, shown in dotted lines, the inner edge of said member 2 would intersect the inner edge of the member 1, as at 7. Having thus adjusted the 5 tool to the angle to be fitted, whether it is placed in the angle, or around the angle, the member 2 is closed until the middle line 5 thereof crosses or intersects the inner edge of the member 1 at the point 7, which would 10 put it in the position B, shown in dotted lines, and thereby accurately indicate the equal division of the angle of the two meeting surfaces, and the angle for the cut in forming a mitered joint. The part of the 15 member 1 which is provided longitudinally thereof, along its inner edge, with the graduation marks or indications, can, with some advantage, be made of thinner material than the other part of said member 1, 20 whereby to bring the graduation marks as close as possible to the surface of the member 2 and thereby somewhat facilitate the accurate adjustment of the parts.

I am aware that changes in the details can 25 be made without departing from the spirit of the invention, and I do not, therefore, limit the invention to the specific form here shown for purposes of illustration, except as I may be limited by the hereto appended 30 claims broadly construed.

I claim:

1. A device of the class described including two members having straight edges and being pivotally connected to be adjusted to 35 different angles relative to each other, one of said members being provided along its inner edge with a series of close, equally spaced graduation marks, the other member having an index mark extending centrally and longitudinally thereof, and parallel with the inner edge of the member the center of the pivot of the members coinciding with the index mark, both said index mark and the inner edge of said other member 40 operating with the graduation marks of the first mentioned member to indicate the relative adjustment of the members to bisect an angle to which the parts are adjusted, the inner edge of said other member, when said 45 parts are adjusted to any angle, indicating by the graduations on the first mentioned member the point to which the index mark of said other member is to be moved to bring the member in position to bisect said angle.
- 50 2. A device for the purpose set forth including two flat members of the same width, each having straight parallel longitudinal edges and being pivoted together near their ends at points coincident with their middles 55 and adapted to be adjusted to different angles relative to each other, one of said members being provided along its inner edge with a series of close, equally spaced graduation 60 marks, the other member having an index line extending centrally and longitudinally 65 thereof parallel with its inner edge, the center of the pivot of the members coinciding with the index line, both said index line and the inner edge of said member co-operating with the graduation marks of the first mentioned member to indicate the relative adjustment of the members to bisect the angle to which the parts are adjusted, said inner edge of one member, when said parts are adjusted to any angle, indicating by the 70 graduations on the first mentioned member the point to which the index line of the said other member is to be moved to bring the member in position to bisect said angle.

3. A miter tool of the character set forth, comprising two members pivotally connected at their ends and adapted to be closed and opened knife fashion, said members having straight inner edges, one of said members being provided along its inner edge with a series of close, equally spaced graduation marks, the other member having an index line extending centrally and longitudinally thereof parallel with its inner edge, the center of the pivot of the members coinciding with the said index line, both the index line and the inner edge of the said member co-operating with the graduations of the other member to indicate the relative adjustment of the members to bisect the angle to which the members are adjusted, said inner edge of the said member, when said parts are adjusted to any angle, indicating by the 75 graduations the point to which the said index line of the said member is to be moved to bring said member in position to bisect said angle.

4. A miter tool comprising two flat members pivotally connected at their ends and having straight parallel edges and rounded ends which are concentric with the pivot, one of said members being provided along its inner edge with a series of close, equally spaced graduation marks, and the other of said members being provided with an index line extending centrally and longitudinally thereof parallel with its inner edge, the center of the pivot of the member coinciding with the said index line of the other member, the inner edge of the said other member, when said members are adjusted to any angle, serving to indicate by the graduations of the first mentioned member the point to which the index line of the said other member is to be moved to bring the said member in position to bisect said angle.

4. A miter tool comprising two flat members pivotally connected at their ends and having straight parallel edges and rounded ends which are concentric with the pivot, one of said members being provided along its inner edge with a series of close, equally spaced graduation marks, and the other of said members being provided with an index line extending centrally and longitudinally thereof parallel with its inner edge, the center of the pivot of the member coinciding with the said index line of the other member, the inner edge of the said other member, when said members are adjusted to any angle, serving to indicate by the graduations of the first mentioned member the point to which the index line of the said other member is to be moved to bring the said member in position to bisect said angle.

5. A miter tool comprising two members with rounded ends and straight edges, pivotally connected at their rounded ends to be adjusted to different angular positions relative to each other, one of said members including two flat metal parts spaced apart and provided along an inner edge with a series of close, equally spaced indicating marks, and the other of said members com-

prising a flat member adapted to close between the parts of said first mentioned member and being provided with an index line extending centrally and longitudinally thereof parallel with its inner edge the center of the pivot for the members coinciding with the said index line, the said other member being adapted to be moved to position the index line into crossing relationship with the indicating marks on the inner edge of the first mentioned member, the inner

edge of the said second member serving to indicate by the graduation marks on the first mentioned member the particular point to which the index line is to be moved to bring said second member in position to bisect the angle.

STEPHEN HAMMER.
